(57) **CLAIM**

The ornamental design for a double sunshade chair, as shown and described.

DESCRIPTION

FIG. 1 is a top, front, right side perspective view of a double sunshade chair, showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 2.

The evenly dashed broken lines illustrate portions of the double sunshade chair and form no part of the claimed design. The unevenly dashed broken lines define the boundaries of the enlarged view and form no part of the claimed design.
